US00D805728S

(12) **United States Design Patent** (10) **Patent No.:** **US D805,728 S**
(45) **Date of Patent:** **** Dec. 26, 2017**

(54) **FOOD PRODUCT**

- (71) Applicants: **Sarah Belt**, West Yorkshire (GB);
Christopher J. Thorogood,
Oxfordshire (GB)
- (72) Inventors: **Sarah Belt**, West Yorkshire (GB);
Christopher J. Thorogood,
Oxfordshire (GB)

(73) Assignee: **Mars, Incorporated**, McLean, VA (US)

(**) Term: **15 Years**

(21) Appl. No.: **29/576,683**

(22) Filed: **Sep. 6, 2016**

(51) **LOC (10) Cl.** **01-01**

(52) **U.S. Cl.**

USPC **D1/199**; D1/127

(57) **CLAIM**

The ornamental design for a food product, as shown and described.

DESCRIPTION

FIG. 1 is a front right perspective view of a first embodiment of a food product showing our new design;

FIG. 2 is a front elevation view of the first embodiment of the food product shown in FIG. 1;

FIG. 3 is a rear elevation view of the first embodiment of the food product shown in FIG. 1;

FIG. 4 is a left side elevation view of the first embodiment of the food product shown in FIG. 1;

FIG. 5 is a right side elevation view of the first embodiment of the food product shown in FIG. 1;

FIG. 6 is a top plan view of the first embodiment of the food product shown in FIG. 1;

FIG. 7 is a bottom plan view of the first embodiment of the food product shown in FIG. 1;

FIG. 8 is a front right perspective view of a second embodiment of a food product showing our new design;

FIG. 9 is a front elevation view of the second embodiment of the food product shown in FIG. 8;

FIG. 10 is a rear elevation view of the second embodiment of the food product shown in FIG. 8;

FIG. 11 is a left side elevation view of the second embodiment of the food product shown in FIG. 8;

FIG. 12 is a right side elevation view of the second embodiment of the food product shown in FIG. 8;

FIG. 13 is a top plan view of the second embodiment of the food product shown in FIG. 8; and,

FIG. 14 is a bottom plan view of the second embodiment of the food product shown in FIG. 8.
